(57) CLAIM

I claim the ornamental design for a gravity feed shelf for a merchandiser, as shown and described.

DESCRIPTION

FIG. 1 is a perspective view of an element of a gravity feed shelf, the broken line showing is for illustrative purposes only and forms no part of the design;

FIG. 2 is a front elevational view of FIG. 1;

FIG. 3 is a rear elevational view of FIG. 1;

FIG. 4 is a right side elevational view of FIG. 1, the left side elevational view of FIG. 1 being in mirror image thereof;

FIG. 5 is a top plan view of FIG. 1; and,

FIG. 6 is a bottom plan view of FIG. 1.

The broken line showing is for illustrative purposes only and forms no part of the design.
